UNITED STATES PATENT OFFICE.

MARIE W. FUCHS, OF BUFFALO, NEW YORK.

GARMENT.

1,016,988.

Specification of Letters Patent. Patented Feb. 13, 1912.

Application filed October 5, 1909. Serial No. 521,152.

To all whom it may concern:

Be it known that I, MARIE W. FUCHS, a citizen of the United States, residing at Buffalo, in the county of Erie and State of 5 New York, have invented a certain new and useful Improved Garment, of which the following is a specification.

This invention relates to an article of 10 wearing apparel in which a flaring effect is produced.

One of the improved features consists in attaching a band of fairly stiff material at its upper edge only to the inner surface of the garment and in such manner that it will 15 hang within the lower portion thereof and produce a flaring or outwardly curving appearance.

Another feature has reference to the construction of the stiffening band from one 20 piece of material and in a substantially oval shape so that the garment when stiffened will hang naturally and gracefully and will have an even and uniform flare completely around the circumference of the lower portion.

The main objects of the invention are to produce a natural flare in the garment having a neat and elegant appearance, to avoid causing uneven or pronounced waves in the 30 flared portion, and to maintain the flared portion of the garment in an easy and graceful position on the wearer.

The stiffening band is arranged with the 35 end portion of the oval in the front of the skirt for a two-fold purpose, viz: First, to provide sufficient stepping room for the wearer; and second, to provide for causing the front portion of the skirt to hang more nearly vertical than the rear portion thereof, 40 because of the greater amount of material in the larger, or wider, portion of the oval than in the smaller or narrower portion.

The invention also relates to certain details of construction which will be hereinafter described and claimed reference being had to the accompanying drawings illustrating a preferred adaptation in which:—

Figure 1 is a fragmentary side elevation partially in section of a skirt provided with 50 the improved flare. Fig. 2 is an enlarged detached plan view of the oval stiffening band. Fig. 3 is a section on line *a a*, Fig. 2. Fig. 4 is a section on line *b b*, Fig. 1, through the skirt, the flounce and the stiffening band

showing the manner of securing them together by a single row of stitching.

In referring to the drawings in detail, like numerals designate like parts.

In the adaptation of the invention illustrated in the accompanying drawings, 1 represents the body portion of a ladies' skirt or petticoat having a lower flounce 2. A band 3 of stiffening material such as mohair, or hair cloth is secured to the lower end of the skirt body 1 and hangs so as to maintain the 65 flounce in a flared out condition as shown in Fig. 1. This band is preferably of an oval shape as shown in Fig. 2 and is formed of one integral section of material so that it will be equally stiff throughout. A covering 70 4 of suitable thin material is fitted on one of the faces of the band with its side edges lapped over the edges of the band as shown in Fig. 2.

In Fig. 3 one way of securing the covering 75 4 to the band is shown. In this figure the inner margin of the band is folded upon itself as shown at 5 to stiffen the flounce and the inner margin of the covering is folded upon the folded marginal portion. The 80 outer margin of the covering is folded over the edge of the band and then folded in a double fold upon itself to provide two folds of the covering on the outer margin of the band as shown at 6, in said Fig. 3. Both the 85 flounce 2 and the band 3 are secured to the lower extremity of the body portion 1 by a single row of stitching 7 as shown in Fig. 4. The flounce is secured to the outer surface and the band to the inner surface of the body 90 portion 1, see Figs. 1 and 4 and both hang downward and outward producing a flaring appearance. The flounce and band are not secured together at any point and are free to move independently of each other below the 95 points of mutual attachment to the body portion, so that the garment when on the wearer will have a natural and graceful appearance.

The advantage of the oval shaped band is 100 that the flounce of the skirt is supported in the most convenient shape for walking. Other advantages reside in the integral construction of the band which produces an even stiffness throughout and in the securing 105 of both the flounce and band to the skirt body by a single row of stitching, which naturally reduces the cost and labor besides

securing the flounce and band to the body at the same horizontal plane so that they will fall and hang together naturally.

I claim—

- 5 A garment comprising a body portion, a lower flounce secured to the body portion, and a substantially oval stiffening band secured at the junction of the body portion and the flounce and with its wider portion
10 in the front part of the garment and having

its lower outer portion free and in sliding contact with the interior surface of the flounce below the bottom edge of the body portion, for causing it to flare substantially as shown and specified.

MARIE W. FUCHS.
